(57) **CLAIM**

The ornamental design for the surface ornamentation for a coin-operated entertainment machine, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyrights whatsoever.

FIG. 1 is a front view of the surface ornamentation for a coin-operated entertainment machine, showing our new design;

FIG. 2 is an enlarged view of the upper portion of the coin operated entertainment machine bearing the design as shown in FIG. 1.

FIG. 3 is an enlarged view of the central portion of the coin operated entertainment machine bearing the design as shown in FIG. 1; and,

FIG. 4 is an enlarged view of the lower portion of the coin operated entertainment machine bearing the design as shown in FIG. 1.

The broken line showing of the entertainment machine is for illustrative purposes only, and forms no part of the claimed design.

Views of the top, bottom, left and right sides and back of the coin operated entertainment machine are not included as they are plain and unornamental.
